UNITED STATES PATENT OFFICE.

BARNETT COHEN, OF NEW YORK, N. Y., ASSIGNOR OF ONE-HALF TO PAUL A. DRUCKLIEB, OF NEW YORK, N. Y.

BOX FOR CIGARETTES AND THE LIKE.

1,164,782.

Specification of Letters Patent. Patented Dec. 21, 1915.

Application filed April 29, 1915. Serial No. 24,626.

To all whom it may concern:

Be it known that I, BARNETT COHEN, a citizen of the United States, and a resident of the city, county, and State of New York, whose post-office address is 131 Prince street, in said city, have invented certain new and useful Improvements in Boxes for Cigarettes and the like, of which the following is a specification.

10 The object of this invention is to provide a box or receptacle for containing cigars, cigarettes and like articles from which the articles can be readily removed and in which the box can be made as small and compact 15 as possible and contain the maximum amount of articles.

These and a number of other objects are secured by my invention, an embodiment of which appears below.

20 For a more particular description of my invention, reference is to be had to the accompanying drawing forming a part hereof, in which—

Figure 1 is a plan view of my improved 25 box partly filled with cigarettes and in an open position; Fig. 2 is a perspective view of the same, the contents being removed; Fig. 3 is a sectional view on the line 3—3 of Fig. 1, looking in the direction of the 30 rows; and Fig. 4 is a sectional view of a portion of the partition strip.

My invention may be employed in boxes of any type and I have shown it applied to a cigarette box of the usual form having 35 a containing portion 1 comprising a bottom 2, front 3, sides 4 and 5 and rear 6. Extending around the interior of the box and secured to the front 3 and sides 4 and 5 is a strip 7. It is to be noted that this strip 40 is of greater height and extends above the sides and front and is omitted at the rear 6 of the box so that this portion is lower than the sides and front, and the upper portion of the tops of the cigarettes are free and accessible at that point and the cigarettes may 45 be readily removed. Boxes have heretofore been constructed with the entire rear or back strip omitted but this has been impractical for the reason that the cigarettes fall 50 from the box easily when the cover is opened.

I have shown the strip 7 and sides 4, 5 and front 3 made separately but if desired this strip may be made integral with

the front and sides. The cover 8 is hinged 55 to the rear strip 6 of the box by a strip 9 of flexible material.

In the containing portion 1 of the box is placed a partition strip 10 formed with suitable upright, flexible partitions 11 for 60 holding the cigarettes upright or parallel to the sides of the box and keeping the tops of the cigarettes adjacent the rear of the box where the upper portions of the same project in the open portion where they can be readily grasped by the fingers and removed from the box. Regardless of the number of cigarettes removed from the box the remainder of the contents will be held upright as before mentioned. As shown 65 herein the strip 10 and partitions 11 are made integral. This is not necessary, however, so long as the partitions are made flexible to accommodate cigarettes or cigars of varying thicknesses. This improved flexible 70 partition strip is particularly adapted for use in connection with oval cigarettes, wherein, as shown in Fig. 4, the cigarettes 12 are held at an angle thereby increasing the containing capacity of the box, for if 80 the cigarettes were contained in the box with their greater width uppermost the box would have to be greatly increased in width to accommodate the same, and if the narrow sides of the cigarettes were uppermost, 85 the box would have to be made deeper to accommodate the same.

From the foregoing, it will be seen that I have provided a box or receptacle in which the contents are held in a thoroughly compact and accessible manner.

Having described one embodiment of my invention, it is obvious that the same is not restricted thereto, but is broad enough to cover all structures that come within the 90 scope of the annexed claims.

What I claim is:

1. A box or receptacle for cigarettes or like articles comprising a containing portion having a bottom and sides, one of which 100 sides is of less height than the others, and a series of partitions extending across the bottom of the box toward said lower side and having their free spaces in line with the edge of said lower side whereby cigarettes placed in said position will have a portion of their ends exposed above the edge 105 of said lower side.

2. A box or receptacle for cigarettes or like articles comprising a containing portion having a bottom and sides, a cover hinged to one of said sides, the side to which said cover is hinged being of less height than the other sides and a series of partitions extending across the bottom of the box toward said lower side and having their free spaces in line with the edge of said lower side whereby cigarettes placed in said position will have a portion of their ends exposed above the edge of said lower side.

3. A box or receptacle for cigarettes or like articles comprising a containing portion having a bottom and sides, one of said sides being of less height than the other sides, a cover for the containing portion hinged thereto and a series of flexible upright partitions extending across the bottom of the box toward said lower side and having their free spaces in line with the edge of said lower side whereby cigarettes placed in said

position will have a portion of their ends exposed above the edge of said lower side.

4. A box or receptacle for cigarettes or like articles comprising a containing portion having a bottom and sides, one of said sides being of less height than the others, a covering for said containing portion hinged to the upper edge of the low side and a series of relatively flexible upright partitions arranged in the bottom of the containing portion of the box and extending toward said lower side and having their free spaces in line with the edge of said lower sides whereby cigarettes placed between the partitions will have a portion of their ends exposed above the edge of said lower side.

Signed at the city, county and State of New York, this 28th day of April, 1915.

BARNETT COHEN.
